UNITED STATES PATENT OFFICE

ALOIS B. SALIGER, OF NEW YORK, N. Y.

AUTOMATIC TIME-CONTROLLED SUGGESTION MACHINE

Application filed October 20, 1928. Serial No. 313,749.

The invention relates to an automatic, time-controlled, suggestion machine.

The object of the invention is to provide an automatic means for utilizing the psychological principle of impressing the unconscious mind with suggestions during sleep, as it has been proven that natural sleep is identical with hypnotic sleep and that during natural sleep the unconscious mind is most receptive to suggestions.

In accordance with the invention a sound reproducing mechanism is provided which is adapted to repeat at automatically predetermined intervals whatever suggestions are contained on a phonetic record used in connection with said sound reproducing mechanism. The sound reproducing mechanism is operated by a suitable motor which may be driven from any desirable source of power and may be initially set up at the most advantageous speed for the successful operation of the device. Means are provided so that the playing will automatically start from a given point on the phonetic record and likewise will cease at a given point. After the record has been played, or that part of it which is desired to be played, the sound reproducing mechanism is returned to its initial position and is ready for its next cycle of operation at the next predetermined interval.

A time-controlled mechanism is used in conjunction with the sound reproducing mechanism to accomplish the desired result. This time-controlled mechanism operates to start the driving means for the sound reproducing mechanism and other suitable means controlled by the sound reproducing mechanism causes the driving means to continue to operate until the sound reproducing means has completed its cycle of performance.

The invention will be further described in the following specification and illustrated in the accompanying drawing forming a part

thereof, in which one simple embodiment of the invention is shown:

Referring to said drawing:

Fig. 1 is a front elevation; and

Fig. 2 is a wiring diagram, parts of the mechanism being in plan and parts in elevation.

In the drawing one simple form of a sound reproducing mechanism is illustrated, said mechanism being merely suggestive of many which can be employed for the purpose. The invention contemplates the use of any of the known sound reproducing mechanisms. In addition to being used for reproducing previously prepared phonetic records the mechanism might be utilized for recording a sound record by the known method of substituting a recording stylus for the reproducing stylus in the sound box or reproducer of the mechanism and providing a suitable sensitive wax record. It would be desirable to use the machine this way if a person wanted to make their own records for suggestions instead of using previously prepared records.

Referring again to the drawing the reference numeral 5 designates a base on which is mounted a pair of standards 6 carrying a supporting member 7.

The supporting member 7 has mounted on its upper side a turntable 8 upon which the sound reproducing record 9 is carried. Secured to the under side of the supporting member 7 is a motor 10. The motor 10 is preferably a slow speed electric motor but a spring motor or any other suitable driving means might be used.

As illustrated the turntable is secured to the shaft 11 of the motor. In accordance with numerous well known methods a reduction gearing, governor and speed control might be interposed between the motor 10 and turntable 8. However in the present invention it is deemed advisable to set the driving means at the proper speed when the device is assembled.

- table for supporting a sound reproducing record, a sound reproducer, and a tone arm, an electric motor for driving said sound reproducing mechanism, a clock mechanism electrically connected to said motor, means carried by the minute hand of said clock mechanism for establishing electrical contacts at predetermined intervals to cause said motor to start, and an electrical contact carried by the tone arm of said sound reproducing mechanism to close an electric circuit and cause said motor to continue its operation until said sound reproducing record has been played and said sound reproducing mechanism is returned to its initial playing position. 60
2. An automatic time-controlled suggestion machine having, in combination, means for supporting a sound reproducing record, a sound reproducer, a tone arm, an electric motor for driving said record supporting means, a clock mechanism electrically connected to said motor, means carried by the minute hand of said clock mechanism for establishing electrical contacts at predetermined intervals to cause said motor to start, and means carried by said tone arm to establish an electric contact and cause said motor to continue to operate until said sound reproducing record has been played and the tone arm has been returned to its initial position. 80
3. An automatic time-controlled suggestion machine having, in combination, a turntable for supporting a sound reproducing record, a sound reproducer adapted to traverse said record, a tone arm carrying said sound reproducer, an electric motor for driving said turntable, a clock mechanism electrically connected to said motor, means carried by the minute hand of said clock mechanism for establishing electrical contacts at predetermined intervals to cause said motor to start, means carried by said tone arm to establish an electric contact and cause said motor to continue to operate until said record has been played, and means for returning said sound reproducer and tone arm to their initial position so that said motor ceases to operate. 95
4. An automatic time-controlled suggestion machine having, in combination, a turntable for supporting a sound reproducing record, a sound reproducer adapted to traverse said record, a tone arm carrying said sound reproducer, an electric motor for driving said turntable, a clock mechanism electrically connected to said motor, a spring finger carried by the minute hand of said clock mechanism for establishing electrical contacts at predetermined intervals to cause said motor to start, a finger carried by said tone arm to cooperate with a fixed contact and establish an electric circuit to cause said motor to continue to operate until said record 130
- has been played, said spring finger carried by the minute hand maintaining its electric circuit until the finger carried by the tone arm establishes its electric circuit, and means for returning said sound reproducer and tone arm to their initial position at which time the finger carried by the tone arm moves away from its fixed contact so that said motor ceases to operate. 70
- In testimony whereof I affix my signature. 75
